UNITED STATES PATENT OFFICE

2,271,382

PLATFORM FOOT AND BODY VIBRATOR

Ray W. Worthington, Los Angeles, Calif.

Application May 6, 1939, Serial No. 272,194

1 Claim. (Cl. 128—33)

My invention relates to that class of apparatus in which provision is made for producing a rapid vibration and applying this vibration to a platform adapted to have placed thereon the feet of a person with the object of increasing the circulation of blood and also to greatly stimulate the nervous system of the person using this apparatus. Then too, it revitalizes tired aching feet and relaxes the entire body and muscles.

Provision is made for setting the machine in operation by a coin controlled electrical circuit. Further provision is made whereby the patient can regulate the intensity or speed of the vibration at will. Also, the intensity is very greatly increased by means of a rectifier tube in the electrical circuit. My invention also includes a diagram of the human nerve system arranged to be visible to the patient while he is using this apparatus and means whereby apparent motion can be imparted to this diagram giving it the appearance of nerve currents in action.

I accomplish these objects by means of the mechanical and electrical apparatus illustrated by the accompanying drawings in which similar numerals refer to similar parts in the several views. Figure 1 is a perspective view showing a type of my invention having a platform on which the patient stands while taking treatment, and also showing the diagram of the nervous system facing him as he stands on the platform. The coin slot and the control are shown at the top of the column. Figure 2 is a modified type of my invention provided with a seat but having the same apparatus and platform on which the patient places his feet. Figure 3 is a fragmentary sectional view showing one method of placing the control mechanism in the arrangement of Figure 2. Figure 4 is a vertical central section of the type shown in Figure 1, part of the apparatus being shown diagrammatically. Figure 5 is a top plan view of the platform assembly with the cover or platform itself removed. Figure 6 is a diagrammatic view of the electrical and mechanical construction of the various elements. Figure 7 is a fragmentary detail of the coin actuated mechanism.

The construction and operation of my device is as follows: The numeral 1 representing a hollow base casting, having mounted therein a hollow vibrator coil 2, this coil having a pair of armatures 3 and 61, the upper armature 3 being supported on the coiled springs 4 by means of the plate extensions 3a, these armatures having opposed flanges 3b and 6a between which are interposed the rubber buffers or snubbers 5 to pro-

tect these elements from injury during the vibration of the armature 3 which would result if the flanges 3b of armature 3 came into actual contact with the flanges 6a of armature 6. Secured to the upper armature 3 is a platform 7 which is further supported by the coiled springs 8. The coiled springs 4 and the coiled springs 8 being separated as shown serve to equalize the pressure under the platform 7 so that it will not tilt easily when stepped upon. Suitable electrical connections 47 and 49, leading to other parts of the device, are made to the hollow vibrator coil 2, which coil 2 is held in place by the clamp members 11 as shown in Figure 5.

At the back of the hollow base 1 and in a position facing a person standing on the vibrator platform 7 and integral with or secured to said base casting 1 is a hollow column 12. This column 12 is provided with a removable door 13 at the back of the said column, the front of the column having an opening 14 adapted to receive a panel suitable to carry instructions and advertising matter. One method of utilizing this panel opening 14 is to have a card or metal having perforated therethrough an outline of the human body showing the lines and ganglia of the nervous system, or in a similar manner showing the arteries and veins of the circulatory system. Means are also provided for illuminating this body diagram 16 in such a manner as to cause apparent animation of the said body diagram. This feature will be more fully described hereinafter.

Secured to the upper part of the column 12 is a hollow cover 17 adapted to contain a rheostat 18 and having on its outer face a knob 19 by which the user can vary the intensity of the vibration. The cover 17 is also provided with a slot and chute 20 suitable to receive a coin 21.

The coin control mechanism is as follows: 22 is an electric motor having a pinion 23 and a gear 24, arranged to produce very slow motion. Secured to the gear 24 is a cam 25 having on its periphery a notch 26. Mounted on said motor 22 but insulated therefrom is a lever arm 27 pivoted at 28 and having on its end adjacent to the said cam 25 a finger 31 adapted to ride on said cam and also adapted to drop into the notch 26. A suitable electric lead wire 29 connects the source 50 of electrical power with one of the terminals 32 of the motor 22. Another connecting electric wire 30 leads to a contact plate 33. A third electrical connection 34 is made between the lever 27 and the other terminal 35 of the motor 22.

The operation of this coin control mechanism

is as follows: A coin 21 having been dropped into the slot and chute 20 will roll down until it rests on the short end of the lever 27, the weight of the coin depressing the lever 27 until it contacts the plate 33, completing the electric circuit through the lever 27 and the connection 34 to the other motor terminal 35. After depressing the short end of the lever 27 the coin 21 passes by gravity out of the chute 20 and downwardly over the end of the lever 27 into the coin box 36. It will be understood that the coin strikes the end of the lever 27 and presses it into contact with the point below that it pauses only momentarily and then rolls into the box 36. The depression of the short end of the lever 27 raises the finger 31 and permits the cam 25 to rotate slowly. As the cam 25 rotates the finger 31 rests on its periphery holding the contact through 29, 34, and 35. When the cam 25 has rotated a full circle the finger 31 drops into the notch 26, lifting the short end of the lever 27, thus breaking the connection and stopping the motor.

The intensity control mechanism consists of the rheostat 18 with its knob and indicator 19 outside of the upper chamber 17 and having mounted on its shaft a ratchet 43 and an escapement lever 41 having a tooth 44 adapted to engage the ratchet 43. This rheostat 18 is also provided with a coil spring 42 which automatically returns the rheostat to a "zero" position when the current is cut off. When the current is on, the magnet 39 is energized by the current through the wires 38 and 38-a, and as soon as the current is cut off by the lever 27 opening the electrical circuit, the escapement lever 41 is drawn upwardly by means of the spring 40 out of engagement with the ratchet 43, which is then returned to "zero" by the spring 42. The machine then remains inoperative until another coin is placed in the slot and chute.

For the purpose of obtaining a more desirable frequency of vibratory action through the vibratory coil 2 a Tungar rectifier tube 45 is used for passing half wave impulses of current through said vibratory coil. A transformer 46 is used in connection with this rectifier tube 45. The primary of the transformer 46 is connected to the "AC" circuit wires 30 and 47, the secondary of the transformer 46 being connected to the filament terminals of the rectifier tube 45, the cathode of this tube being connected to the rheostat 18 by means of the wire 48, and the vibrator coil 2 being connected to wire 47 on one side and wire 49 on the other side, this latter wire being connected to the rheostat 18.

The method of obtaining the appearance of animation in the body diagram 16 is as follows: The card or plate 50 has perforated through its thickness this diagram 16 which outlines the

nervous system or the circulatory system. This plate is held stationary in position back of the column opening 14. Back of this stationary plate 50 is a moving plate 51 which is provided with a great number of very small openings 52. This plate 51 is pivoted and suspended at its upper end 53, being given an oscillatory movement by means of the copper disc motor 54. This copper disc motor 54 consists of two magnets 55 having a disc armature 56 which is geared down to very slow motion by the pinion 57. The gears 58 actuate the crank disc 59, the crank pin of which is connected to the moving plate 51, this motor being operated by electrical current through the wires 30 and 60. Behind the plates 50 and 51 is an electric light bulb 61 which is supplied with current by means of the wires 62 and 63.

In the form illustrated by Figures 2 and 3 a seat 64 supported by the springs 65 is provided to enable the patient to have vibratory foot treatment while comfortably seated. In this type all of the mechanism shown and described in the other views is contained in the case 66 with the exception of the animated body diagram.

It will be understood that many variations in the detailed construction and operation may be made without departing from the spirit of my invention.

What I claim as my invention and desire to secure by Letters Patent is:

In a platform foot and body vibrator comprising a base, a hollow vibrator coil located in said base, means for holding said vibrator coil in a fixed location, a pair of armatures on either side of said vibrator coil one of which is freely movable, said freely movable armature having a plate extension, core pieces on said armatures inside the said coil, a platform secured to said freely movable armature and forming a top surface on which a person may stand, the other of said armatures being secured to the inside of said base, two sets of coiled compression springs located on the inside of said base and resting on the bottom thereof, the tops of one set of said springs bearing directly on the underside of said platform, and the tops of the other set of springs bearing on the under side of said plate extension on said freely movable armature, said springs being of sufficient resistance to support a person without flexure when standing on said platform, opposed flanges on said armatures outside of said vibratory coil and having buffers between their faces, an electric circuit and a rectifier tube for passing half wave impulses of current through said vibratory coil, and a coin controlled switch for closing said circuit to start the operation of said vibrator.

RAY W. WORTHINGTON.
